(62.) [DESIGN.] WILLIAM G. CROSS.

Frame for a Mirror.

No. 5,457. Patented Jan. 2, 1872.

UNITED STATES PATENT OFFICE.

WILLIAM G. CROSS, OF PHILADELPHIA, PENNSYLVANIA, ASSIGNOR TO HALL AND GARRISON.

DESIGN FOR A FRAME FOR A MIRROR.

Specification forming part of Design No. 5,457, dated January 2, 1872.

Specification describing a Design for a Frame for Mirrors, &c., invented by WILLIAM G. CROSS, of Philadelphia, Pennsylvania.

The nature of my design is fully represented in the accompanying drawing, which shows one-half only of the frame, the latter consisting of the base A, two side columns B, and the entablature D. The base consists of a plain molding, a, carried round the foot b of each column, where it forms the lowest member of a base, d, supporting the ornament e, the character of which is too clearly indicated in the drawing to need description, the said ornament and its base standing out from the face of the column, as shown. Each column is also ornamented at the top by a figure, f, standing out from the face of the column, and the latter, which may be of any length, has on its face, between the figures f and e, a tablet, h, of the character shown. There is on the outside of each column, immediately below the entablature, a side ornament, i. At the junction of each column with the entablature there is an ornamental medallion, j. The entablature is characterized by a plain lower bead, k, and a plain upper molding, m, which, at m', follows the shape of an offset of the entablature, this offset being immediately above the column. The portion m' of the molding is surmounted with an ornament, n, in line with the column. In the center of the entablature there is a shield, p, over the top of which the molding m is continued in an arched form, as shown at m²; and the entablature is surmounted with a central ornament, q, terminating at an offset, s, in the molding. The details of this central ornament are too clearly shown in the drawing to need description. On each side of the central shield the entablature has an ornament, t, and between the latter and the column there is on the entablature a tablet, v. On each side of the main central ornament of the entablature, and on the top of the same, there is an ornament, w, and below the entablature there is a rib, x x, which is a continuation of the inner edges of the two columns, and which follows the course pointed out.

I claim as my invention—

1. The design of the base b d of the column of a frame, substantially as described and shown.
2. The design of the ornament e, substantially as illustrated and described.
3. The design of the ornamental lower portion of the column of a frame, the said lower portion comprising the members b, d, and e.
4. The ornament f, substantially as shown and described, on the face of the column of a frame.
5. The design for the column of a frame ornamented with the members b, d, e, f, i, and tablet h.
6. The ornament j at the junction of the entablature and column, substantially as illustrated and described.
7. The molding m m¹ m² pursuing the course described and illustrated, and forming the upper edge of the entablature.
8. The design of the central shield p and arched molding m², substantially as shown and described.
9. The design of the central ornament q of the entablature, substantially as shown and described.
10. The ornament t, substantially as illustrated and described.
11. The ornamental apex n of the entablature in line with the column, substantially as shown and described.
12. The ornament w on the top of the entablature, substantially as illustrated and described.
13. The design of the rib x x, following the course pointed out.
14. The design for the entire entablature, substantially as illustrated and described.
15. The design for a frame, substantially as described, and as illustrated in and by the accompanying drawing.

In testimony whereof I have signed my name to this specification in the presence of two subscribing witnesses.

WILLIAM G. CROSS.
